[57] CLAIM

The ornamental design for a housing for operating of control systems, as shown and described.

DESCRIPTION

FIG. 1 is a perspective view of a housing for operating of control systems, according to one preferred embodiment of this invention;

FIG. 2 is a front view of the housing for operating of control systems, as shown in FIG. 1;

FIG. 3 is a side view of the housing for operating of control systems, as shown in FIG. 1;

FIG. 4 is a side view, opposite the side view shown in FIG. 3, of the housing for operating of control systems, as shown in FIG. 1;

FIG. 5 is a rear view of the housing for operating of control systems, as shown in FIG. 1;

FIG. 6 is a top view of the housing for operating of control systems, as shown in FIG. 1;

FIG. 7 is a bottom view of the housing for operating of control systems, as shown in FIG. 1; and,

FIG. 8 is a perspective view of a housing for operating of control systems, according to another preferred embodiment of this invention.

The undisclosed views of the second embodiment are identical to those of the first.
